FOOTBALL GAME APPARATUS

Vincent De Palma, East Haven, Conn.

Application June 29, 1949, Serial No. 102,021

11 Claims. (Cl. 273—94)

1

The present invention relates in general to games and more particularly to game apparatus for playing a game of football which may be contested by two competing players and which simulates regulation football.

An object of the invention is to provide a superior game apparatus which is durable, relatively inexpensive, and wherein the judgment and mental dexterity of competitive players will determine, in large part, the outcome of the game.

A further object of the invention is to provide a superior football-game apparatus wherein the outcome of the game depends upon the measure of each player's skill as a quarterback in a football game.

A further object of the invention is to provide a superior football-game apparatus wherein players compete with each other, each player being able to make offensive and defensive plays for scoring points in accordance with regulation football rules.

A still further object of the invention is to provide a football-game apparatus adapted to be operated by two competing players who use a marble or ball for effecting a play, each player having under his control a plurality of slides, by means of which he may exercise control over the passage of the ball from a ball-receiver to the yardage-areas of the apparatus.

A still further object of the invention is to provide a football-game apparatus embodying a ball-receiver, on opposite sides of which two players are adapted to stand and to manipulate, without the knowledge of the other player, suitable slides for exercising control over the passage of a ball from a ball-receiver to a plurality of yardage-areas which are connected to the receiver by suitable chutes.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a left-side elevation of the football-game apparatus of this invention;

Fig. 2 is a right-side elevation of the football-game apparatus of this invention;

Fig. 3 is an enlarged top plan view of the football-game apparatus of Figs. 1 and 2 but with the cover removed and showing the disposition of the ball-receiver relative to the yardage-areas of

the apparatus and the chutes connecting the yardage-areas with the ball-receiver;

Fig. 4 is a left-side elevation in section on line 4—4 of Fig. 3 showing details of the closed ball-receiver, the chutes connecting the ball-outlet ports of the latter with the yardage-areas, and the slides for closing and opening the ball-outlet ports;

Fig. 5 is an enlarged rear elevation of the apparatus on section line 5—5 of Fig. 4 showing additional details of the chutes connecting the ball-outlet ports of the closed ball-receiver with the yardage-areas of the apparatus, and the gates for recovering a ball when a play is blocked;

Fig. 6 is a perspective view of one of a pair of guide-blocks used to slidably support the operating-slides of the game apparatus;

Fig. 7 is an enlarged front elevation in section on line 7—7 of Fig. 4 showing details of the chutes connecting opposite sides respectively of the closed ball-receiver;

Fig. 8 is an enlarged broken rear elevation on section line 8—8 of Fig. 4 showing a ball-outlet port in the bottom of the closed ball-receiver, closed off from the corresponding chutes by means of the manually-operated slides;

Fig. 9 is an enlarged fragmentary plan elevation in section on line 9—9 of Fig. 4 showing a ball-outlet port of the closed ball-receiver closed by means of the manually-operated slides;

Fig. 10 is a perspective view of one of a pair of manually-operated slides for closing and opening a ball-outlet port of the closed ball-receiver;

Fig. 11 is a perspective view of the second of the pair of manually-operated slides for closing and opening a ball-outlet port of the closed ball-receiver; and

Fig. 12 is a plan view of a football-field board used in conjunction with the apparatus of Figs. 1 through 11 for following the movement of the football in playing out the game.

General construction

Referring especially to Figs. 1 through 4, the football-game apparatus of this invention comprises a box-like member indicated generally at 15, having a substantially-rectangular base 16, a pair of substantially-vertical side walls 17 and 18 respectively, a back wall 19, and a front wall 20, all of which elements are formed of a relatively-inexpensive material such as, for example, composition board, plywood, or an equivalent material. The base 16 extends forwardly of the front wall 20 of the box-like member, as at 16',

and is provided with substantially triangular-shaped side walls 17' and 18' respectively which constitute integral extensions of the corresponding side walls 17 and 18 of the box-like member 15. A partition 21 extends across the upper part of the box-like member 15 and divides the the interior of the latter into upper and lower chambers 22 and 23 respectively, the partition 21 constituting the floor board of the upper chamber 22 and being inclined forwardly and downwardly, as shown especially well in Fig. 4, so as to form a sloping surface for feeding a ball by gravity from the back of the upper chamber 22 to the forward end thereof, for the purpose hereinafter described. The top of the box-like member 15 is closed by a cover 24 which is permanently fastened over the top of the upper chamber 22. The latter is then, in effect, a completely closed chamber and is hereinafter referred to as a "closed ball-receiver." A partition 25 is secured uprightly on the floor 21 of the upper chamber 22 substantially intermediate its opposite sides 17 and 18 so as to divide the upper chamber into two separate ball-compartments 26 and 27 respectively.

As shown especially well in Fig. 3, the front edge of the floor 21 of the upper chamber is intersected at two longitudinally-spaced points therealong by substantially U-shaped ball-outlet ports 28 and 29 respectively, each of which extends through the floor 21 and constitutes a ball-outlet port of one of the compartments 26 and 27 respectively of the closed ball-receiver 22.

Secured to the underside of the floor 21 adjacent its front edge and extending longitudinally thereof, is a pair of slide-guide blocks 30 and 31 having longitudinal channels 32 and 33 respectively in their upper faces, the channels being substantially U-shaped in cross section and extending beneath the respective ball-outlet ports 28 and 29 of the compartments 26 and 27. Referring especially to Fig. 6, longitudinal channels 32 and 33 respectively have spaced-parallel substantially-vertical walls which are provided with longitudinal inwardly-projecting tongues 34—34 and 35—35 respectively substantially intermediate the top and bottom edges of the walls, these tongues serving as a guide-means for supporting the manually-operated slides of the game apparatus, as and for the purpose hereinafter described. Cut through the bottom of the channels 32 and 33 of the respective guide-blocks immediately beneath the respective U-shaped ball-outlet port 28 and 29 of the ball-compartments 26 and 27, are substantially-rectangular apertures 36 and 37 respectively, the over-all dimensions of each aperture corresponding substantially to the over-all dimensions of the respective ball-outlet ports 28 and 29. Cut through the front walls of the channeled guide-blocks substantially opposite the apertures 36 and 37 respectively thereof, are substantially U-shaped clearance-grooves 38 and 39, the width of each clearance-groove corresponding substantially to the width of its respective channel-aperture 36 and 37, and the depth of each groove corresponding substantially to the depth of its respective channel. These U-shaped clearance-grooves 38 and 39 of the channeled guide-blocks are disposed immediately opposite transversely-spaced apertures 40 and 41 respectively formed in the front wall 20 of the box-like member 15, as shown especially well in Fig. 3. Projecting from the front face of the front wall 20 in a substantially-horizontal plane, is a platform 42 which extends beneath each of

the apertures 40 and 41 and is provided on its front edge with an upright guard-rail 43, the opposite ends of which are fastened securely to the face of the front wall 20 adjacent the corresponding ends of the platform, to provide an enclosure for holding a ball on the platform 42.

Formed at the forward end of the extension 16' of the base 16 are four disk-shaped areas hereinafter referred to as "yardage-areas" 44, 45, 46 and 47 respectively, each having a plurality of indentations, indicated generally at 48, arranged in concentric circles in its respective base; and a relatively-low wall circumscribing its base as indicated at 49, 50, 51 and 52 respectively.

Connecting each of these yardage-areas with the closed ball-receiver 22 of the apparatus is an inclined chute 53, 54, 55, and 56 respectively, each of which is preferably substantially U-shaped in cross section and formed of any suitable material such as, for example, stiff cardboard, thin sheet metal, or an equivalent relatively-inexpensive material. The lower end of each chute intersects the corresponding wall of its respective yardage-area, while the upper ends of the chutes are connected to the aforesaid guide-blocks. More particularly, the two chutes 53 and 54 on the left side of the apparatus (as seen in Fig. 3) are connected at their upper ends in side-by-side relationship in the single guide-block aperture 36 which is in communication with the ball-outlet port of the left-hand compartment 26 of the closed ball-receiver. The lower end of the chute 53 intersects the wall 49 of the yardage-area 44 substantially tangential to the outer side thereof, while the lower end of the chute 54 intersects the wall 50 of the yardage-area 45 substantially tangential to its outer side. Similarly, the upper ends of the two inclined chutes 55 and 56 on the right-hand side of the apparatus are connected in side-by-side relationship in the single guide-block aperture 37 which is in communication with the ball outlet-port of the right-hand compartment 27 of the closed ball-receiver 22, while the lower ends of the respective chutes 55 and 56 intersect the respective walls 51 and 52 of the yardage-areas 46 and 47 respectively, substantially tangential to the outer sides thereof.

The yardage-areas at the left-hand side of the apparatus, as seen in Fig. 3, are for "passes," the area 44 being for short passes and kickoffs and the area 45 being for long passes and punts. The yardage-areas 46 and 47 on the right-hand side of the apparatus are for "runs," the area 46 being for short runs, and the area 47 for long runs, extra points and field goals.

It will be appreciated that the identification of these areas of the apparatus is specifically commensurate with the use of the apparatus for playing a game of football, but that it is within the purview of the invention to identify these areas with the characteristic actions of other games.

Referring to Figs. 3, 4 and 7, the upper chamber or closed ball-receiver 22 is provided with a pair of chutes 57 and 58 respectively, which are substantially U-shaped in cross section and formed of any suitable inexpensive material such as cardboard, thin metal or the like, each chute being supported at its outer end substantially opposite to and in communication with a substantially-rectangular aperture 59 and 60 respectively formed in the upper rear corners of the respective side walls 17 and 18 of the ball-receiver 22. The inner ends of the respective chutes 57 and 58 are supported by and extend over the aforesaid partition 25 of the upper

chamber or ball-receiver 22, to which end the upper edge of the partition is provided with substantially U-shaped notches to receive the corresponding portions of the respective chutes. As noted especially well in Figs. 3 and 7, the inner end of the chute 57 in the left-hand compartment 26 of the upper chamber 22 extends across the partition 25 into the right-hand compartment 27, while the inner end of the chute 58 in the right-hand compartment extends across the partition 25 into the left-hand compartment 26 of the upper chamber 22, both chutes being inclined downwardly therein. It will be obvious that by introducing a ball into one or the other of the rectangular apertures 59 and 60 respectively in the corresponding side wall of the ball-receiver 22, the ball will pass down the corresponding chute into the compartment in the opposite side respectively thereof.

Provided in the side walls 17 and 18 respectively of the box-like member adjacent the rectangular apertures 59 and 60 respectively thereof, are round apertures 61 and 62 respectively which provide access to the corresponding compartments 26 and 27 of the closed ball-receiver 22. For carrying out the characteristic actions of a regulation football game, in the manner hereinafter described, the rectangular aperture 59 in the left-hand side of the receiver is identified by the word "run," while the rectangular aperture 60 in the right-hand side of the receiver is identified by the word "pass." Likewise, the round aperture 61, in the left-hand side of the receiver is identified by the word "pass," while the round aperture 62 in the right-hand side of the receiver is identified by the word "run." Clearly, then, when a ball is introduced into the "run" aperture in the left-hand side of the receiver or into the "pass" aperture in the right-hand side of the receiver, the ball will be conveyed by the corresponding chute into the opposite compartment of the receiver and will roll down the inclined floor thereof to the ball-outlet port at its front edge. Similarly, a ball introduced into the "pass" aperture in the left-hand side of the receiver or in the "run" aperture in the right-hand side of the receiver will drop into the adjacent compartment of the receiver and roll down the inclined floor thereof to the ball-outlet port at its front edge. In this connection, in order that a ball in either one of the compartments of the receiver may be guided into its corresponding ball-outlet port, each compartment is provided at its front end with a pair of upstanding ball-deflecting boards 63-63 and 64-64 respectively, each pair of ball-deflecting boards converging from its upper ends inwardly and downwardly to the corresponding ball-outlet ports 28 and 29 of the respective compartments 26 and 27. Thus, it will be clear that whenever a ball is dropped into the left-hand compartment, either by way of the round "pass" aperture 61 in the left-hand side of the receiver, or by way of the chute 58 of the rectangular "pass" aperture 60 in the right-hand side of the receiver, the ball will roll down the inclined floor board of the compartment and be guided into the ball-outlet port 28 thereof by the converging ball-deflecting boards 63-63. Similarly, a ball introduced into the right-hand compartment by way of the round "run" aperture 62, or the chute 57 of the oppositely-disposed rectangular "run" aperture 59 will roll down the inclined floor board 21 of the compartment and be guided by the ball-

deflecting boards 64-64 into the ball-outlet port 29 of the right-hand compartment 27.

Ball-controlling means

5 By referring to Fig. 4, it will be clear that a ball which has been introduced into either the right- or left-hand compartment of the closed ball-receiver, in the manner hereinabove described, will roll down to the ball-outlet port of 10 its respective compartment, and that in this position the ball will be immediately opposite one or the other of the clearance-grooves 38 and 39 in the front walls of the slide-guide blocks, and the corresponding aperture 40 and 41 respectively 15 in the front wall 20 of the box-like member. Consequently, were it not for suitable gate-means located immediately rearwardly of the respective apertures 40 and 41 in the front wall 20 of the receiver, a ball in either one of the 20 compartments would roll freely out onto the enclosed platform 42. To control egress of a ball from the compartments by way of the apertures in the front wall of the receiver, manually-operated gate-means, indicated generally at 65 and 25 66 respectively, are provided immediately rearwardly of the rear face of the front wall 20 for covering its apertures 40 and 41, each gate comprising a substantially-rectangular plate 67 and 68 respectively of thin sheet metal or equivalent 30 material, the outside dimensions of which are greater than the corresponding dimensions of the aforesaid apertures 40 and 41 in the front wall of the receiver; and lift-rods 69 and 70 respectively secured at their lower ends to the upper 35 edges of the respective plates 67 and 68 substantially intermediate the opposite ends thereof. The upper ends of the respective lift-rods 69 and 70 project through guide-apertures in the cover of the receiver and are provided at their upper 40 extremities with suitable handholds 71 and 72 respectively. Mounted on the lift-rods between the underside of the cover and the upper edges of the respective plates, are coil-springs 73 and 74 respectively, the compression of each spring 45 being adapted normally to hold its respective plate down over the corresponding aperture 40 and 41 respectively in the front wall of the receiver.

By referring to Fig. 3, it will be clear that the 50 oppositely-disposed edges of the plate of each gate-means are adapted to engage in vertical grooves formed in the inner ends of the corresponding converging ball-deflecting boards, whereby the plates are held adjacent the rear 55 face of the front wall 20 of the receiver and guided thereby during vertical displacement. Thus, it will be evident that normally the gates are resiliently held down by their respective springs 73 and 74 to close-off the apertures 40 and 41 in the front wall 20 of the receiver, thereby preventing a ball in either compartment of the closed ball-receiver 22 from escaping inadvertently onto the enclosed platform 42. However, when it is desired to remove a ball from 60 either one of the closed compartments of the closed ball-receiver, under the circumstances hereinafter described, the corresponding gate may be drawn up manually substantially vertically to uncover the corresponding aperture in the front wall of the device, so as to enable the ball to roll out onto the enclosed platform.

Additional control-means are provided for controlling the movement of a ball from the compartments of the closed ball-receiver to the 75 yardage-areas hereinabove described. As shown

especially well in Figs. 8, 9, 10 and 11, these additional control-means constitute two pairs of manually-operated slides 75—76 and 75'—76'. Inasmuch as the corresponding slides of each pair of slides are substantially identical in construction, except for such obvious alterations as are necessary to accommodate the respective pairs of slides for operation in the left-hand side and right-hand side respectively of the ball-receiver, the description which follows will be confined to the pair of slides 75—76, adapted for use in the right-hand side of the apparatus, the corresponding parts of the left-hand slides having similar reference characters applied thereto plus a prime (').

Referring to Fig. 10, the operating-slide 75 comprises a strip of relatively-thin sheet-metal stock or equivalent material having a substantially-rectangular reach 77 reduced at its outer end to provide a pair of stop-shoulders 78; and a finger-grip portion 79 provided with a downwardly-bent lip 80. Formed integrally at the opposite end of the reach 77 and extending at substantially right angles thereto in the plane thereof, is a leg 81, the outer end of which is bent upwardly at substantially right angles as at 82 and supports a substantially-rectangular slide-leaf 83 in a plane above and substantially parallel to the plane of the reach 77, the slide-leaf 83 extending forwardly of and at substantially right angles to the leg 81 of the slide. Formed vertically in the slide-leaf 83 is a ball-escape aperture 84. As mentioned above, the operating-slide 75 of Fig. 10 is designed for use in the right-hand side of the receiver. The operating-slide 75' for the left-hand side of the receiver is substantially identical to the slide 75, except that its right-angle leg 81' extends from its corresponding reach 77' in the opposite direction.

The second slide 76 of the pair of operating-slides for use in the right-hand side of the apparatus is shown in Fig. 11 and comprises a relatively-short substantially-rectangular sheet-metal member having a slide-leaf portion 85 provided in its front edge with a U-shaped ball-escape aperture 86. Extending from the outer end of the slide-leaf 85 is an integral finger-grip portion 87 of reduced width, which forms stop-shoulders 88—88' at the outer end of the slide-leaf. A depending lip 89 is formed on the outer end of the finger-grip 87, and extending laterally from one side of the slide-leaf is a lug 90, the inner edge of which constitutes a stop-shoulder 91. The operating-slide 76 shown in Fig. 11 is adapted particularly for use in the right-hand side of the receiver, but it will be appreciated that the operating-slide 76' for the left-hand side of the receiver is substantially identical, except that the ball-escape aperture 86' and the laterally-projecting lug 90' are on opposite edges respectively of the slide-leaf 85'.

The respective pairs of operating-slides 75—76 and 75'—76' are adapted to be slidably mounted in the game apparatus in a substantially-horizontal plane, immediately beneath the underside of the floor board 21 of the receiver 22 and adjacent the rear face of the front wall 20 thereof, for controlling the escape of a ball from either one of the ball-outlet ports of the compartments of the closed ball-receiver to the respective chutes of the yardage-areas. To these ends, the relatively-long slides 75 and 75' respectively are supported at their respective outer ends by the reaches 79 and 79' in horizontal slots formed in

the corresponding side walls of the receiver, the slots being disposed rearwardly of a vertical plane intersecting the ball-outlet ports of the respective ball-receiving compartments, so that the reaches of the respective slides pass to the rear of the aforesaid ball-outlet ports and, more particularly, rearwardly of the vertical legs of the chutes 53, 54, 55 and 56. However, due to the substantially right-angle bend which the slide-leaf supporting-leg of each operating-slide makes with its respective reach, the slide-leaves 83 and 83' of the respective slides will be positioned immediately beneath the respective ball-outlet ports of the ball-receiving compartments. More particularly, the slide-leaf 83 of the operating-slide 75 in the right-hand side of the apparatus will be disposed beneath the ball-outlet port 28 of the left-hand compartment, while the slide-leaf 83' of the operating-slide 75' in the left-hand side of the apparatus will be disposed beneath the ball-outlet port 29 of the right-hand compartment. The inner ends of the slides 75 and 75' respectively are slidably supported by the guide-blocks of their respective compartments by engagement of the longitudinal edges of the respective slide-leaves 83 and 83' in the guide-grooves, which are defined by the bottoms of the channels of its respective guide-blocks and the inwardly-extending tongues of the walls thereof, as shown especially well in Fig. 4.

The relatively-short operating-slides 76 and 76' are supported at their outer reduced ends in horizontal slots in the respective side walls of the receiver, the inner ends of the slides being supported by engagement of the slide-leaf portions 85 and 85' respectively thereof in guide-grooves of the corresponding guide-blocks, the grooves of which are defined by the upper edges of the tongues thereof and the underside of the floor board 21 of the closed receiver 22.

Each slide is adapted to be moved in and out relative to its corresponding slot in the wall of the box-like member 15, the inner movement of each operating-slide 75 and 75' respectively being limited by engagement of its respective portion 82 and 82' with the adjacent end of its respective guide-block; and the outer movement of each operating-slide 75 and 75' respectively being limited by engagement of its stop-shoulder 78 and 78' respectively with the corresponding side walls of the receiver. In a similar manner, the inner movement of each of the operating-slides 76 and 76' respectively is limited by engagement of its respective stop-shoulder 91 and 91' with the outer ends of the corresponding guide-block, while the outward movement of each slide 76 and 76' respectively is limited by engagement of its stop-shoulder 88 and 88' with the corresponding side wall of the receiver.

By reference to Figs. 3 and 5, it will be clear that by moving the left-hand slide 75' in and out, the ball-escape aperture 84' of its slide-leaf will be moved sequentially into registry with the upper end of the chute 56 and the upper end of the chute 55 respectively at the right-hand side of the apparatus. Similarly, by moving the right-hand slide 75 in and out, its ball-escape aperture 84 will be moved sequentially into registry with the upper end of the chute 53 and the upper end of the chute 54 in the left-hand side of the apparatus. Likewise, by moving the operating-slide 76' in the left-hand side of the apparatus in and out, its ball-escape aperture 86' will be moved sequentially into alignment with the upper ends of the chutes 53 and 54 in the left-hand side of the

apparatus, and, similarly, by moving the operating-slide 76 in and out, its ball-escape aperture 86 will be moved sequentially into alignment with the upper ends of the two chutes 55 and 56 in the right-hand side of the apparatus, as and for the purposes hereinafter described. Thus, while the operating-slides 75—76 and 75'—76' have been and are hereinafter referred to as the respective right and left pairs of operating-slides of the game apparatus, it will be appreciated that insofar as the slides are used conjunctively for controlling the egress of a ball from either of the two compartments, the slide 75 and the slide 76' coact to control the egress of a ball from the left-hand compartment 26, and the slides 75' and 76 coact to control the egress of a ball from the right-hand compartment 27.

As pointed out at the outset, the device of this invention is especially adapted for use in simulating a football game and, consequently, suitable indicia are provided to indicate to the players the functions of the respective elements of the apparatus. Thus, the operating-slide 75' in the left-hand side of the apparatus is identified by the word "run," while the operating-slide 75 in the right-hand side of the apparatus is identified by the word "pass." The operating-slide 76' in the left-hand side of the apparatus is identified by the word "pass," while the operating-slide 76 in the right-hand side of the apparatus is identified by the word "run."

The four yardage-areas of the game apparatus are provided also with suitable indicia, as shown especially well in Fig. 3, for indicating the number of yards gained in any one play, the number of yards gained being indicated by a number in the center of each of the indentures of the yardage-areas. Further, the indentures of the yardage-areas 44 and 45, designated as "short pass" and "long pass," respectively are provided with numbers above and below the indentures. These numbers are associated with kick plays, the number above the indenture being the length of the kick, and the number below the indenture being the length of the run-back. The "long-run" section of the yardage-area 47 is used also for extra points after touchdown and for field goals, and to these ends the indentures of this section are provided with letters G and NG standing for "good" and "not good" respectively.

Adapted to be used in conjunction with the game apparatus is a football-field board 92 (see Fig. 12) laid out to represent a regulation football field, the board being provided with parallel rows of apertures 93 and 94 running along the side lines and centrally thereof respectively, and spaced apart to represent one yard. A peg 95 may be inserted in the apertures 94 of the board to indicate the position of the ball after each play, while two pegs 96—96 connected by a chain 97, are provided for the apertures 93 to represent linesmen, the chain 97 being of such length that the linesmen's pegs 96—96 are spaced apart a distance equal to ten yards.

Operation of game apparatus

The operation of the game apparatus may be described in general as follows.

The two pairs of operating-slides 75—76 and 75'—76' are used by the offense and the defense respectively, or vice versa, for controlling the movement of a ball or marble which completes each play. As indicated by the indicia on opposite sides respectively of the apparatus, one operating-slide of each pair of slides is for

controlling running plays, and the other slide is for controlling passes, each slide being movable in and out relative to its respective slot in the side of the member 15 for selecting either a long or short play, as the case may be. In this respect, it will be appreciated that the two positions referred to above of the respective slides effect a long or short play by permitting a ball to escape from its compartment by way of the proper chute into the yardage-area corresponding to a long or short play. For indicating to the players these two positions of the slides, the outwardly-projecting reaches thereof may be provided with inner and outer color bands. Thus, when the slides 75 and 75' are moved inwardly to bring their outer color bands up to the slots in the corresponding side walls of the box-like member 15, their ball-escape apertures 84—84' respectively will overlie the upper ends of the chutes 54 and 56 respectively for effecting either a long pass or a long run. If these same slides are pulled outwardly to bring their inner color bands out to the slots in the corresponding side walls of the box-like member 15, then the ball-escape apertures 84 and 84' of these slides will overlie the upper ends of the chutes 53 and 55 respectively for effecting a short pass or a short run. Conversely, if the defense anticipates that the offense is going to try a long run, then the defense sets his slide for a short run, that is to say, assuming that he is on the left-hand side of the apparatus, he pulls his slide 75' outwardly, thereby moving the ball-escape aperture 84' of his slide out of alignment with the upper end 35 of the chute 56. Consequently, the imperforate portion of the slide-leaf 83' of his slide extends across the upper end of the long-run chute 56, thereby preventing the ball from entering the chute and hence effectively blocking the play. The slides 76 and 76' operate in a similar manner but in the reverse order, i. e., when the slides are moved inwardly to bring their outer color bands up to the slots in the corresponding side walls of the box-like member 15, the ball-escape apertures 86 and 86' respectively of these slides are moved into alignment with the upper ends of the chutes 55 and 53 respectively for effecting short plays, that is to say, either a short run or a short pass. Conversely, by moving the slides 50 76 and 76' outwardly, they may be used defensively to block a short run or a short pass. From the foregoing description, it will be clear that in playing a game, the offense may select and set his operating-slides so as to make one 55 of four possible plays, that is to say, either a short or long pass, or a short or long run, whereas the defense may set his operating-slides so as to block two of the four possible plays, that is to say, he may set one slide for blocking a 60 pass and one slide for blocking a run. Assuming, by way of example, that the offense is stationed at the left side of the apparatus and has set his operating-slide 75' for effecting a long run which, incidentally, he does not 65 dis- close to his opponent; and that the latter has adjusted his operating-slides to settings which in his judgment and experience he believes will block the forthcoming play of the offense, then the offense inserts a marble or ball in the rectangular aperture 59 in his side of the box-like member 15. The ball will roll down the chute 51 into the closed compartment 27 in the right-hand side of the closed ball-receiver to the ball-outlet port 29 in the front edge thereof. In 70 the event the defense has been astute enough

to move his operating-slide 76 so as to cut off the ball-outlet port 29 from the ball-escape aperture 86' of the offense's slide, then the ball is effectively blocked from escaping into the upper end of the chute 56 and no gain is made. This blocked play will constitute one down for the offense. The blocked ball is then retrieved from the closed compartment 27 of the receiver 22 by lifting the gate 66 so as to permit the ball to roll out onto the enclosed platform 42. However, if the defense had not anticipated the offense's play so that as a consequence the defense's slide 76 did not cut off the ball-outlet port 29 from the escape-aperture 84' of the offense's slide, then the ball would be free to drop down into the upper end of the chute 56, and to be conveyed thereby to the yardage-area for scoring a long run, the length of which is indicated by the number in the bottom of the indenture in which the ball comes to rest. In a similar manner, yardage gains may be attempted in the other yardage-areas of the game apparatus. The scoring is done on the football-field board 92 shown in Fig. 12, each advance of the ball being marked by moving the peg 95 forwardly in the central line of apertures 94 of the football-field board and each first down being marked by the linesmen's pegs 96-96.

Rules of the game

By operating the two pairs of slides in the manner described above and by following a prescribed set of rules, two opponents may play a game of football which follows very closely to regulation football.

To this end, it is a rule of the game that kicks at any time cannot be blocked and consequently when either side wishes to kick such as, for example, on kickoff, or punting for a field goal, or for an extra point after touchdown, he must announce his intention to his opponent.

For the kickoff, both sides set their respective pairs of slides for effecting a short pass. The marble will come to rest in one of the indentures of the corresponding yardage-area 44 and the number above the indenture will indicate the length of the kick, while the number below the indenture will indicate the run-back. As is done in regulation football games, the length of the kick is measured off from the 40-yard line, this measurement and the run-back being made on the football-field board 92 to establish the position of the ball for first down and 10 yards to go, the position of the ball being indicated by the peg 95.

For effecting a punt, both sides set their slides for a long pass. When the ball comes to rest in one of the indentures of the yardage-area 45 corresponding to long passes, the number above the indenture is the length of the punt, and the number below the indenture is the length of the run-back, the ultimate position of the ball being marked on the football-field board by the peg 95 in the manner hereinabove described.

For field goals or an extra point after touchdown, both sides set their slides for a long run. No field goal may be attempted until the offense is within 30 yards of the goal, and the successful completion of the field goal or extra point is evidenced when the marble stops in one of the indentures of the long-run yardage-area 41 having the letter G therein, which stands for "good." If the marble stops in an indenture

having the letters NG therein, then the kick was "no good," that is to say, unsuccessful.

A further rule of the game is that in the event the marble does not come to rest in any indenture of the yardage-areas, it constitutes a 5-yard penalty against the defense, whereupon the offense has the option of accepting the five yards and sacrificing the down, or refusing the five yards and taking the down over again. It will be noted, further, that some of the indentures are identified by the letters OB which denotes a fumble. If a ball comes to rest in an indenture so marked, the opponent recovers the ball (opponent's ball) on the scrimmage line. The game also provides for intercepted passes which are indicated by the letters Inter. in some of the indentures of the yardage-areas 44 and 45. When a ball comes to rest in one of these indentures, the offense gains the number of yards marked in the indenture, but the defense takes possession of the ball. As noted above, when making a punt, both sides set their slides for a long pass, and to add further interest to the game, the rules provide that if the ball comes to rest in one of the indentures bearing the letters Inter., the punt is to be regarded as blocked and the ball then passes to the opponent on the scrimmage line. For alacrity and interest, it is a rule of the game that the marble must be put into play within ten seconds or else the team carrying the "ball" will be penalized five yards for delaying the game.

In brief then, a game is started in the usual manner by flipping a coin to determine which team will make the kickoff. Both sides will then set their operating-slides for a short pass as prescribed by the rules and the marble is then dropped by the offense into the pass-hole at the top of the closed ball-receiver. Since there is no opposition to the movement of the ball into the chutes, the ball will move down into the yardage-area 44 for a short pass, the length of the kick being indicated by the numbers at the top of the indenture in which the marble rests, and the length of the run-back being indicated by the number below the indenture. The scrimmage line is then marked on the football-field board in the manner indicated above, and the teams are then ready for first down and ten yards to go. Subsequent plays are carried out by manipulation of the respective pairs of operating-slides, in the manner hereinabove described and in accordance with the prescribed rules.

By playing the game accordingly, the two opposing teams may experience the same competitive spirit and may be called upon to exercise the same degree of judgment and intuition as is required in regulation football, the element of chance being a minor factor in scoring points. Although the apparatus does not embody means for indicating each down as it is played, it is within the purview of the invention to include means on the football-field board for keeping track of each down, or to use a plurality of different-colored balls, ball-tripping means, or balls marked with numbers to indicate the sequence of plays.

As pointed out earlier, the apparatus shown herein and described above is particularly adapted for playing a football game, but it is also within the purview of the invention to adapt the apparatus for playing games of a similar nature, the present apparatus being readily adapted to these purposes by alteration of the indicia carried thereon.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A game apparatus comprising a play-scoring area; a closed ball-receiver arranged above said play-scoring area and having a ball-inlet and a ball-outlet port; ball-conveying means connected at its upper end to the said ball-outlet port of said ball-receiver and at its lower end to said play-scoring area for delivering a ball thereto by gravity; and play-control means for controlling the egress of a ball from the said outlet-port of said ball-receiver to said ball-conveying means for scoring a play, said control-means comprising an apertured slide arranged between the said ball-outlet port of said receiver and the upper end of said ball-conveying means and operated by one player of said game, to select, without disclosure to a second player, any one of a plurality of offensive plays; and a second apertured slide arranged between the said ball-outlet port of said receiver and the upper end of said ball-conveying means and operated by a second player to select without disclosure to the other player, any one of a plurality of defenses against any one of said offensive plays.

2. A game apparatus comprising a play-scoring area; a closed ball-receiver arranged above said play-scoring area and having a ball-inlet and a ball-outlet port; ball-conveying means connected at its upper end to the said ball-outlet port of said ball-receiver and at its lower end to said play-scoring area for delivering a ball thereto by gravity; play-control means for controlling the egress of a ball from the said outlet-port of said ball-receiver to said ball-conveying means for scoring a play, said control-means comprising an apertured slide arranged on one side of said closed ball-receiver between the said ball-outlet port of said receiver and the upper end of said ball-conveying means and operated by one player of said game to select, without disclosure to a second player, any one of a plurality of offensive plays; and a second apertured slide arranged on the opposite side of said closed ball-receiver between the said ball-outlet port of said receiver and the upper end of said ball-conveying means and operated by said second player to select, without disclosure to the other player, any one of a plurality of defenses against any one of said offensive plays; and gate-means carried by said closed ball-receiver for retrieving a ball therefrom.

3. A game apparatus comprising a plurality of play-scoring areas; a closed ball-receiver arranged above said play-scoring areas and having ball-inlet and ball-outlet ports and a floor board, said floor board being inclined downwardly from said ball-inlet ports to said ball-outlet ports to cause a ball in said receiver to roll by gravity from said inlet-ports down to said outlet-ports; ball-conveying means connected at their upper ends to the said ball-outlet ports of said ball-receiver and at their lower ends to said play-scoring areas for delivering a ball thereto by gravity; and play-control means for controlling the egress of a ball from the said ball-outlet ports of said ball-receiver to said ball-conveying means for scoring a

play, said control-means comprising a set of apertured slides arranged between the said ball-outlet ports of said ball-receiver and the upper ends of said ball-conveying means and operated by one player of said game to simultaneously select, without disclosure to a second player, any one of a plurality of offensive plays and any one of a plurality of gains to be attempted by the selected offensive play; and a second set of apertured slides arranged between the said ball-outlet ports of said ball-receiver and the upper ends of said ball-conveying means and operated by said second player to select, without disclosure to the other player, a plurality of defenses against any one of said offensive plays.

4. A game apparatus comprising a plurality of play-scoring areas; a closed ball-receiver arranged above said play-scoring areas; a partition in said closed ball-receiver arranged to divide said closed ball-receiver into two separate compartments, each compartment having a ball-inlet port, a ball-outlet port and an inclined floor, the inclined floor of each compartment being arranged to cause a ball in the corresponding compartment to roll by gravity from the ball-inlet port of the compartment to its ball-outlet port; ball-conveying chutes connected at their upper ends to the said ball-outlet ports of said compartments and at their lower ends to said play-scoring areas for delivering a ball thereto by gravity; and play-control means for controlling the egress of a ball from the ball-outlet ports of said compartments to the ball-conveying chutes thereof for scoring a play, said control-means comprising a set of apertured slides arranged on one side of said closed ball-receiver between the said ball-outlet ports of said receiver and the upper ends of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of said offensive plays.

5. A game apparatus comprising a plurality of play-scoring areas; a closed ball-receiver arranged above said play-scoring areas; a partition in said closed ball-receiver arranged to divide said closed ball-receiver into two separate compartments, each compartment having a ball-inlet port, a ball-outlet port and an inclined floor, the inclined floor of each compartment being arranged to cause a ball in the corresponding compartment to roll by gravity from the ball-inlet port of the compartment to its ball-outlet port; ball-conveying chutes connected at their upper ends to the said ball-outlet ports of said compartments and at their lower ends to said play-scoring areas for delivering a ball thereto by gravity; ball-deflecting means in each compartment for guiding a ball therein into the respective ball-outlet port thereof; and play-control means for controlling the escape of a ball from the ball-outlet ports of said compartments to the corresponding ball-conveying chutes for scoring a play, said control-means comprising a set of apertured slides arranged on one side of said closed ball-receiver between the said ball-outlet ports of said receiver and the upper ends

of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of the offensive plays.

6. A game apparatus comprising a plurality of play-scoring areas; a closed ball-receiver arranged above said play-scoring areas; a partition in said closed ball-receiver arranged to divide the said closed ball-receiver into two separate compartments, each compartment having a ball-inlet port, a ball-outlet port and an inclined floor, the inclined floor of each compartment being arranged to cause a ball therein to roll by gravity from its respective ball-inlet port to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas; and play-control means for controlling the egress of a ball from the ball-outlet ports of said compartments to the corresponding pairs of ball-conveying chutes for scoring a play, said control-means comprising a set of apertured slides arranged on one side of said closed ball-receiver between the said ball-outlet ports of said receiver and the upper ends of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of said offensive plays.

7. A game apparatus comprising a plurality of play-scoring areas; a closed ball-receiver arranged above said play-scoring areas; a partition in said closed ball-receiver arranged to divide the said closed ball-receiver into two separate compartments, each compartment having a pair of ball-inlet ports, a ball-outlet port and an inclined floor, the inclined floor of each compartment being arranged to cause a ball therein to roll by gravity from one of its respective ball-inlet ports to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas.

receiver to its play-scoring areas; a pair of ball-conveying chutes in said closed ball-receiver, each of said chutes connecting one of the ball-inlet ports of one compartment with the opposite compartment of said ball-receiver whereby a ball introduced into the said one ball-inlet port of one compartment is conveyed by its respective chute to the outlet-port of the opposite compartment; and play-control means for controlling the escape of a ball from the ball-outlet ports of said compartments to the corresponding ball-conveying chutes for scoring a play, said control-means comprising a set of apertured slides arranged on one side of said closed ball-receiver between the said ball-outlet ports of said receiver and the upper ends of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of the offensive plays.

8. A game apparatus comprising a plurality of play-scoring areas; a closed ball-receiver arranged above said play-scoring areas; a partition in said closed ball-receiver arranged to divide the said closed ball-receiver into two separate compartments, each compartment having a pair of ball-inlet ports, a ball-outlet port and an inclined floor, the inclined floor of each compartment being arranged to cause a ball therein to roll by gravity from one of its respective ball-inlet ports to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas; a pair of ball-conveying chutes in the said closed ball-receiver, each of said chutes connecting one of the ball-inlet ports of one compartment with the opposite compartment of said ball-receiver whereby a ball introduced into the said one ball-inlet port of one compartment is conveyed by its respective chute to the outlet-port of the opposite compartment; gate-means supported by said closed ball-receiver opposite each separate compartment thereof for retrieving a ball from each compartment; and play-control means for controlling the escape of a ball from the ball-outlet ports of said compartments to the corresponding ball-conveying chutes for scoring a play, said control-means comprising a set of apertured slides arranged on one side of said closed ball-receiver between the said ball-outlet ports of said receiver and the upper ends of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of the offensive plays.

ports of said receiver and the upper ends of said ball-conveying chutes and operated by said second player to select, without disclosure to the other player, a plurality of defenses against any one of the offensive plays.

9. A game apparatus comprising a plurality of play-scoring areas having indentures provided with indicia; a closed ball-receiver arranged above said play-scoring areas; a partition in said closed ball-receiver arranged to divide the said closed ball-receiver into two separate compartments, each compartment having a ball-inlet port, a ball-outlet port and an inclined floor, the inclined floor of each compartment being arranged to cause a ball therein to roll by gravity from its respective ball-inlet port to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas; gate-means supported by said closed ball-receiver opposite each separate compartment thereof for retrieving a ball from each compartment; an enclosed platform opposite said gates for receiving a ball from said gates; and play-control means for controlling the escape of a ball from the ball-outlet ports of said compartments to the corresponding ball-conveying chutes for scoring a play, said control-means comprising a set of apertured slides arranged on one side of said closed ball-receiver between the said ball-outlet ports of said receiver and the upper ends of said ball-conveying chutes and operated by one player of said game to simultaneously select, without disclosure to a second player, any one of a plurality of offensive plays and any one of a plurality of gains to be attempted by the selected offensive play; and a second set of apertured slides arranged on the opposite side of said closed ball-receiver between the said ball-outlet ports of said receiver and the upper ends of said ball-conveying chutes and operated by said second player to select, without disclosure to the other player, a plurality of defenses against any one of the offensive plays.

10. A game apparatus comprising a plurality of play-scoring areas; a closed ball-receiver arranged above said play-scoring areas; a partition in said closed ball-receiver arranged to divide the said closed ball-receiver into two separate compartments, each compartment having a ball-inlet port, a ball-outlet port and an inclined floor, the inclined floor of each compartment being arranged to cause a ball therein to roll by gravity from its respective ball-inlet port to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas; play-control means comprising two mutually-coacting independently-operable sets of slides; slide-supporting guide-means secured to the underside of said inclined floors for slidably supporting said mutually-coacting independently-operable slides between the ball-outlet ports of the compartments and at the upper ends of the two pairs of ball-conveying chutes, one of said sets of slides being arranged to be operated by one player of said game to simultaneously select, without disclosure to a second player, any one of a plurality of offensive plays and any one of a plurality of gains to be attempted by the selected offensive play; and the second set of apertured slides being arranged to be operated by said second player to select, without disclosure to the other player, a plurality of defenses against any one of said offensive plays, thereby to control the egress of a ball from the ball-outlet ports of the compartments to the corresponding pairs of ball-conveying chutes for scoring a play; and stop-means for limiting the sliding movement of said mutually-coacting independently-operable apertured slides.

apertured slides; and slide-supporting guide-means secured to the underside of said inclined floors for slidably supporting said mutually-coacting independently-operable slides between the ball-outlet ports of the compartments and the upper ends of the two pairs of ball-conveying chutes, one of said sets of apertured slides being arranged to be operated by one player of said game to simultaneously select, without disclosure to a second player, any one of a plurality of offensive plays and any one of a plurality of gains to be attempted by the selected offensive play; and the second set of apertured slides being arranged to be operated by said second player to select, without disclosure to the other player, a plurality of defenses against any one of said offensive plays, thereby to control the egress of a ball from the ball-outlet ports of the compartments to the corresponding pairs of ball-conveying chutes for scoring a play.

11. A game apparatus comprising a plurality of play-scoring areas; a closed ball-receiver arranged above said play-scoring areas; a partition in said closed ball-receiver arranged to divide the said closed ball-receiver into two separate compartments, each compartment having a ball-inlet port, a ball-outlet port and an inclined floor, the inclined floor of each compartment being arranged to cause a ball therein to roll by gravity from its respective ball-inlet port to its ball-outlet port; a pair of ball-conveying chutes connected at their upper ends in the ball-outlet port of one compartment and at their lower ends to two of said play-scoring areas respectively; a second pair of ball-conveying chutes connected at their upper ends in the ball-outlet port of the second compartment and at their lower ends to two other play-scoring areas respectively, each of said pairs of ball-conveying chutes being adapted to deliver a ball by gravity from its respective compartment of said ball-receiver to its play-scoring areas; play-control means comprising two mutually-coacting independently-operable sets of slides; slide-supporting guide-means secured to the underside of said inclined floors for slidably supporting said mutually-coacting independently-operable slides between the ball-outlet ports of the compartments and at the upper ends of the two pairs of ball-conveying chutes, one of said sets of slides being arranged to be operated by one player of said game to simultaneously select, without disclosure to a second player, any one of a plurality of offensive plays and any one of a plurality of gains to be attempted by the selected offensive play; and the second set of apertured slides being arranged to be operated by said second player to select, without disclosure to the other player, a plurality of defenses against any one of said offensive plays, thereby to control the egress of a ball from the ball-outlet ports of the compartments to the corresponding pairs of ball-conveying chutes for scoring a play; and stop-means for limiting the sliding movement of said mutually-coacting independently-operable apertured slides.
